LATTICE TYPE GRILLE

Filed June 29, 1945

UNITED STATES PATENT OFFICE

2,520,222

LATTICE TYPE GRILLE

Leland George Stone, Fort Wayne, Ind., assignor
to The Magnavox Company, Fort Wayne, Ind.,
a corporation of Delaware

Application June 29, 1945, Serial No. 602,384

2 Claims. (Cl. 154—43)

1

The present invention relates to a lattice type grille and more particularly to a grille adapted for use with loud speakers in radio and phonograph cabinets.

In cabinets housing loud speakers as for example in radio receivers and electric phonographs, it is desired to provide a cover for the face of the loud speaker. Numerous arrangements have been attempted, some of which included a wire mesh member covered with a cloth frequently retained in position by an ornamental grille or scroll work. Where the individual areas of the loud speaker grille cloth are fairly large, it frequently occurs that the cloth becomes displaced so as to sag and become unattractive. Accordingly it is desirable to obviate this disadvantage and at the same time to provide a loud speaker opening or grille work which is relatively simple to manufacture and which at the same time permits a certain amount of latitude or variations in design and appearance of the grille.

In accordance with the present invention it is proposed to take a sheet of material and to rout the material on one side to a certain depth and then to rout the material on the other side to at least a complementary depth so as to form openings where the grooves intersect each other. Such grille is susceptible of various different appearances as will subsequently become apparent.

It is therefore an object of the present invention to provide a new and improved method of fabricating a lattice type grille.

It is another object of the present invention to provide a simple economical and yet attractive lattice type grille for loud speakers.

Other and further objects of the present invention will subsequently become apparent by reference to the following description taken in connection with the accompanying drawing wherein

Figure 1 is a perspective view of the application of the present invention to a cabinet such as might be used for housing a radio receiver;

Figure 2 illustrates the first step in the manufacture of a lattice type grille in accordance with the present invention;

Figure 3 illustrates the second step in the manufacture of a grille;

Figure 4 is a cross sectional view of a grille constructed in accordance with the present invention such as the grille shown in Figure 1 as seen in the direction of the arrows along the line 4—4; and

Figure 5 is a perspective view of a lattice type

2

grille constructed in accordance with the present invention and having a further step in the manufacture applied thereto.

Figure 1 shows a cabinet 11 such as a radio cabinet having a loud speaker opening provided with a grille 11 which illustrates the appearance of a grille constructed in accordance with the apparatus and mode of manufacture about to be described. Figure 2 shows the first step in manufacture of a grille in accordance with the present invention wherein a flat sheet of material 13 is being cut in one direction by a plurality of dado cutters 14 arranged to rout the material 13 so as to produce simultaneously a plurality of longitudinally extending recesses or grooves 15.

After the routing operation of the sheet of material 13 has been completed in accordance with the showing in Figure 1 wherein each of 20 the grooves 15 preferably is cut to a depth slightly greater than half the thickness of the material 13, the next step is performed as shown in Figure 3. In Figure 3 the plurality of routing cutters 14 cut a plurality of grooves 16 in 25 a direction at an angle to the previous grooves 15. The various grooves 16 may be of the same general arrangement as the grooves 15, or may be of greater or lesser width. The grooves 16 produced by the routing operation at an angle 30 to the grooves 15 preferably are of such depth as to be slightly in excess of the depth necessary to engage the first formed grooves 15 thereby to form at the intersection a plurality of openings. It will be appreciated that the cuts 15 and 16 may be of different depth, the only requirement being that the second set of cuts must be sufficient to intersect the grooves formed by the first routing operation. It also has been found preferable in many instances to rearrange 35 the routing cutters for the second operation so as to provide openings in the panel having an aggregate area equal to about sixty per cent of the total area of the sheet of material 13. Of course by spacing the dado cutters 14 in different 40 manners for the different cuts, various effects or designs may be produced so that the emphasis may be produced upon horizontal or vertical bars in any particular arrangement.

From the cross section view in Figure 4 it will 50 readily be seen that the cuts or routing operation 16 intersecting the previously formed openings 15 so that rectangular openings are provided where the routing grooves 15 and 16 are arranged at right angles to each other.

If desired a grille formed in the manner illus-

trated may be finished in any one of a number of different manners so as to provide a variety of design. It has been found convenient to utilize plywood as the material. This material may be finished in natural wood finish or painted in any color. The grooves may be arranged in horizontal or vertical directions and may be of different spacings so as to give emphasis to different appearances. Where it is desired to emphasize either a vertical or horizontal bar appearance, one side of the lattice type grille is coated with an adhesive and a grille cloth is applied to the grille. For example such grille cloth might be applied to the back of the grille so that a unique effect would be obtained with bars in one direction being predominant and a lesser predominance of the bars at right angles and still a third effect of depth showing the grille cloth. It is also contemplated to apply adhesive to one surface of the grille and place a grille cloth thereupon. Thereafter a jig or forming die is used to press inwardly the grille cloth into the grooves as shown in Figure 5 wherein the grille cloth 17 has been applied to the grille 12 and pushed inwardly so as to adhere to the cross bars of the grille. With the grille covered entirely by a cloth or fabric as shown in Figure 5, the grille may be used for either horizontal or vertical design emphasis.

From the foregoing it will be appreciated that there has been provided an improved lattice type grille which may be made of any type of material at a relatively low manufacturing cost. Where plywood is used the material is relatively easy to work and is inexpensive. By varying the adjustment of the routing cutters many variations in design may be obtained. The grille cloth when applied is retained in position so as to obviate the possibility of the cloth being stretched or caused to sag and become unattractive.

While for the purpose of illustrating and describing the present invention it has been convenient to show in the drawing a grille formed with grooves at regular intervals and of substantially the same size on both sides at right angles to each other, it is to be understood that such disclosure is not to be considered a limitation since such variations in the application of the method are contemplated as have heretofore been suggested and as may be commensurate with the spirit and scope of the invention set forth in the following claims.

This invention is hereby claimed as follows:

1. A lattice type grille comprising a sheet of plywood having a plurality of parallel grooves on its outwardly disposed face surface to define a plurality of parallel front bars; a plurality of parallel grooves on the back surface of the grille at a right angle to the face grooves and of a depth sufficient to intersect the grooves on the face surface to provide a plurality of openings through the grille, with the width of the grooves 10 being greater than the width of the bars to provide openings throughout the grille having an aggregate area equal to about sixty per cent of the total area of the grille to facilitate transmission of sound therethrough; and a grille cloth 15 extending across the face of the grille and adhesively secured to the three exposed sides of the front bars throughout their entire area and to the forwardly exposed surfaces of the rear bars at points intermediate the grille openings whereby 20 the grille cloth is supported throughout a substantial area of the grille and is thus prevented from sagging.

2. A lattice type grille comprising a sheet of plywood having a plurality of parallel grooves on its outwardly disposed face surface of the plywood to define a plurality of parallel front bars; a plurality of parallel grooves on the back surface of the grille at a right angle to the face grooves and of a depth sufficient to intersect the grooves on the face surface to provide a plurality of openings through the grille; and a grille cloth extending across the face of the grille and adhesively secured to the three exposed sides of the front bars throughout their entire area and to 30 the forwardly exposed surfaces of the rear bars at points intermediate the grille openings whereby 35 the grille cloth is supported throughout a substantial area of the grille.

LELAND GEORGE STONE.
